Primary Examiner — Sheryl Lane*Assistant Examiner* — Mark T. Philipp(74) *Attorney, Agent, or Firm* — Medley, Behrens & Lewis LLC; Lorri W. Cooper(57) **CLAIM**

The ornamental design for a pump housing, as shown and described.

DESCRIPTION

FIG. 1 is a top perspective view of an example pump housing depicting an inventive waistband for the pump housing;

FIG. 2 is a bottom perspective view of the pump housing of FIG. 1;

FIG. 3 is a front plan view thereof;

FIG. 4 is a rear plan view thereof;

FIG. 5 is a top plan view thereof;

FIG. 6 is a bottom plan view thereof;

FIG. 7 is a right-side plan view thereof; and,

FIG. 8 is a left-side plan view thereof.

The uniform dashed broken lines depict portions of the pump housing and form no part of the claimed design.

The dash-dot-dash lines define the bounds of the claimed design and form no part thereof.

1 Claim, 7 Drawing Sheets(56)
